F. W. WINTER

SPRAY TUBE FOR POWDER

Filed July 15, 1924

Friedrich Wilhelm Winter ^{Inventor}

By

B. Singer

Attorney

UNITED STATES PATENT OFFICE.

FRIEDRICH WILHELM WINTER, OF VIENNA, AUSTRIA.

DESIGN FOR A SPRAY TUBE FOR POWDER.

Application filed July 15, 1924. Serial No. 10,159. Term of patent 7 years.

To all whom it may concern:

Be it known that I, FRIEDRICH WILHELM WINTER, a citizen of the Republic of Austria, residing at Vienna XIII, Austria, have invented a new, original, and ornamental Design for Spray Tube for Powder, of which the following is a specification, reference being had to the accompanying drawing, forming part thereof.

The figure is an elevation of a spray tube for powder, showing my new design.

I claim:

The ornamental design for a spray tube for powder, as shown.

FRIEDRICH WILHELM WINTER.

Witnesses:

JOSEPH TURMANN,
ANTON GOETZ.
